UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

AUTOMATIC TELEPHONE SYSTEM.

1,194,851.

Specification of Letters Patent. Patented Aug. 15, 1916.

Application filed January 14, 1916. Serial No. 72,148.

To all whom it may concern:

Be it known that I, ALBEN E. LUNDELL, a citizen of the United States, residing at New York, in the county of Bronx and State of New York, have invented certain new and useful Improvements in Automatic Telephone Systems, of which the following is a full, clear, concise, and exact description.

This invention relates to telephone systems in which automatic or electrically operated switches are employed in establishing connections from calling to called lines.

The object of the invention is the provision of such a system in which the switching devices are controlled entirely over a single non-talking conductor, and more particularly to a system of this type in which controlling magnets operating on close margins will be avoided.

The switches employed in the present invention may be of any desired structure in which the brushes are first moved to a group of contacts under the control of one magnet and are then moved to a certain set of magnets in the selected group under the control of a second magnet. A switch of this general character is shown in patent to Keith *et al* No. 815,716.

The accompanying sheet of drawings diagrammatically indicate the apparatus and circuits employed in the present embodiment of this invention.

The side switch employed may be similar in character to the one disclosed in said Keith patent, but is arranged to move its wipers in certain instances upon the energization instead of upon the deenergization of its actuating magnet. A side switch operating in this manner is disclosed in an application of Oscar F. Forsberg, Serial No. 6302, filed February 5, 1915. The side switch herein disclosed is moved from position 1 to position 2 upon the first energization of its controlling or escape magnet, from position 2 to position 3 upon the second deenergization of its escape magnet, and from position 3 to position 4 upon the next energization of its escape magnet.

The calling device indicated at the station of the subscriber's line may be of any desired character in which a series of interruptions are produced in the line circuit. A circuit arrangement for a sending device

of this character is disclosed in applicant's Patent No. 1,148,912.

It is believed that the invention will now be readily understood from the description of the manner in which the switches are controlled in establishing a connection.

In the drawings, 1 and 2 represent connecting circuit terminals which are brought into association with the terminal contacts of the calling line in any desired manner.

3 and 4 represent normally open contacts in the selected connecting circuit which are closed immediately following the association of the connecting circuit with the calling line.

5 is the impulse relay by means of which the actuating impulses are transmitted to the stepping magnets of the switches.

If the present invention is employed in a semi-automatic instead of a full automatic system, the stepping relay 5 will be operated by the central operator's sending device 75 instead of by impulses transmitted from the calling subscriber's station.

Batteries of different potential are indicated in the drawings. Certain of these batteries which are indicated as being merely of two cells, may be of 24 volts potential. The other batteries indicated as being of four cells, may be of 48 volts potential. It is to be understood of course that all of these may be different portions 85 of the same battery.

We will now assume that the calling line 3 has been extended to the selector switch brushes 9, 10 and 11. Relay 5 will be energized closing a circuit from battery through the contact and armature of impulse relay 5, wiper 13 and the right winding of the escape magnet 14 at the first selector switch to ground. Magnet 14 is energized and moves the side switch wipers from position 1 to position 2. In moving to position 2 a circuit is completed from the 48 volt battery, through relay 15, wiper 13, and the armature and contact of relay 15 to ground through the 24 volt battery. Relay 15 will attract its armature, thus completing a circuit for the slow release relay 16.

The calling subscriber will now operate his dial to cause a series of interruptions in the substation circuit. With each interruption of said circuit, relay 5 will retract its

armature, opening the circuit for relay 15, which will in turn retract its armature. Relay 16 being slow to release remains up throughout the series of impulses. With 5 each deenergization of relay 15, a circuit is completed from the 48 volt battery through the primary stepping magnet 17 and the escape relay 18 in parallel, and thence through the front contact and armature of 10 relay 16 and the back contact and armature of relay 15 to ground. Magnet 17 and relay 18 will both be energized, and relay 18 will close a circuit from battery through the left winding of the escape magnet 14, armature 15 and contact of relay 18, wiper 19 and the right winding of magnet 14 back to battery, thus energizing the escape magnet. The side switch, however, will not be operated this time until the escape magnet is deenergized. 20 Relay 18 being slow to release is held up during the series of impulses. Magnet 17 rapidly attracts and retracts its armature, moving the brushes 9, 10 and 11 of the selector switch from group to group of the 25 trunk terminals.

Upon the termination of the series of impulses, relay 5 will remain energized, and will hold the circuit for relay 15 closed. Relay 18 will then retract its armature, opening 30 the circuit for the escape magnet 14 and causing the side switch to move to position 3. As the side switch moves to position 3 the circuit for relay 15 is interrupted, and it retracts its armature, but a substitute 35 circuit is completed for the holding relay 16 through the side switch wiper 13 in position 3, thus preventing the release of the switch.

The escape magnet 14 is employed as a 40 test relay. In position 3 of the side switch, a circuit is closed from the 24 volt battery through resistance 20, wiper 19 and the right winding of relay 14 to ground. The current flowing over this circuit, is, however, 45 insufficient to cause magnet 14 to pull up its armature. At this time a circuit is closed from battery through the left winding of magnet 14 and wiper 21 to the test brush 19 of the selector switch. The test 50 or guarding contacts of trunks leading to idle second selector switches will be connected to ground through a side switch wiper as 13' at the second selector and the left winding of the escape magnet 14' of 55 that switch. If, however, a trunk leading to such switch is busy, its test or guarding contact will be provided with battery potential. This may be supplied in several different manners, depending on the stage of 60 operation of the switch which has selected the connecting circuit, and of the switch at which the circuit terminates. If the connecting circuit has just been selected at one of its multiples and the side switch of this 65 connecting circuit has moved to position 2,

it is obvious that the test contacts will be connected to the 48 volt battery through wiper 13' and stepping relay 15'. At this time, however, the 24 volt battery at the impulse relay 5 will also be connected to said 70 test contact by a circuit extending through wipers 13 and 21, in position 4. Therefore, the potential of the test contact will be of substantially 24 volts, and current will therefore not flow through the left winding of 75 magnet 14 in such a manner as to cause its energization. If the calling subscriber connected to the connecting circuit is at this time transmitting impulses, the battery at the impulse relay 5 will be removed from 80 the multiple test contacts of the connecting circuit with each deenergization of relay 5, leaving only the 48 volt battery at relay 15 associated with said contacts. The flow of current, however, from this battery through 85 the left winding of magnet 14, is in a direction to oppose the flow of current through its right winding, and magnet 14 will not be energized. If the side switch wiper of 90 the switch at which the connecting circuit terminates is in position 3 or position 4, the same condition will exist, except that the test contact will be connected to the 48 volt battery through relay 16' instead of through 95 relay 15'. If the switch associated with a 100 multiple of the connecting circuit is just in the process of testing and the side switch has not yet moved to position 4, the second switch to arrive on the multiple test contact will find battery potential thereon and its test relay or magnet 14 will not be energized. When the second selector side switch was moved to position 3, a circuit was established 105 from battery through the secondary stepping magnet 22, wiper 23 and interrupter 105 24 to ground. This circuit will be maintained and the brushes 9, 10 and 11 will be stepped from trunk to trunk until the contacts of an idle trunk are engaged, when current will flow through the left winding 110 of magnet 14 in a direction to assist the current flowing through its right winding, thus energizing the escape magnet and moving the side switch to position 4.

It is obvious from the preceding description in what manner succeeding selector switches would be operated. The secondary magnet of the connector switch might be arranged to be substituted by a side switch wiper for the primary magnet in the circuit controlled by relay 15. It is believed this is obvious and will not require further description.

In the present embodiment of the invention, the release of the switches is controlled 115 solely by the calling subscriber in replacing his receiver upon its hook. When this occurs the holding relays 16 of all of the switches will be deprived of current and will release their armatures, causing the re- 120 125

turn to normal of their respective switches. This release circuit at the first selector switch may be traced from battery through the release magnet 26, off-normal contact 27, 5 back contact and armature of relay 16 and back contact and armature of relay 15 to ground.

By the use of batteries of different potentials in the present invention, the necessity 10 for controlling relays operating on narrow margins has been avoided, thus making it possible to produce a practical telephone system in which the automatic switches are controlled solely over a single non-talking 15 conductor.

What is claimed is:

1. In a telephone system, an electrically operated switch, a conductor extending to said switch, a guarding contact for said 20 switch connected to said conductor, a source of current, means for joining said source to said conductor; a controlling magnet for said switch, means for joining said magnet to said conductor, and a second source of 25 current of different potential from said first mentioned source in series with said controlling magnet.

2. In a telephone system, an electrically operated switch, a conductor extending to 30 said switch, a guarding contact for said switch connected to said conductor, a battery, an impulse relay for joining said battery to said conductor, a stepping magnet for said switch, means for joining said magnet 35 to said conductor, and a second battery of different potential from the first mentioned battery in series with said stepping magnet, whereby battery potential is continuously applied to said guarding contact.

3. In a telephone system, an electrically operated switch, a connecting circuit extending to said switch, a guarding contact for said connecting circuit in one of the 45 conductors of said circuit, a source of current, means for connecting said source to said conductor, a controlling magnet for said switch, means for joining said magnet to said conductor, and a second source of 50 current of different potential from said first mentioned source in series with said magnet.

4. In a telephone system, an electrically operated switch, a conductor extending to said switch, multiply connected guarding contacts for said switch, one of said contacts 55 being in said conductor, a source of current, means for joining said source to said conductor, a stepping magnet for said switch, means for joining said magnet to said conductor, and a second source of current of 60 greater potential than said first mentioned source in series with said controlling magnet.

5. In a telephone system, an electrically operated switch, a conductor extending to 65 said switch, multiply connected guarding

contacts for said switch, one of said contacts being in said conductor, an impulse relay for joining said battery to said conductor, a stepping magnet for said switch, means for joining said magnet to said conductor, and a second battery of different potential from the first mentioned battery in series with said stepping magnet, whereby battery potential is continuously applied to 70 said guarding contacts.

6. In a telephone system, connecting circuits, multiple test contacts for said circuits respectively, means for connecting the test contacts of busy circuits with a source of current, a switch, a brush for said switch, means for moving said switch to cause said brush to traverse the test contacts of said circuits, a test magnet for said switch, a pair of windings on said magnet, means to provide a flow of current through one of 85 said windings which is insufficient to operate said magnet, and a circuit for said other winding, including said brush and said contacts successively, the flow of current through the second winding from the test 90 contacts of busy circuits, being in a direction to oppose the flow through said first mentioned winding.

7. In a telephone system, connecting circuits, multiple test contacts for said circuits 95 respectively, means for supplying said test contacts with varying potential according as said circuits are busy or idle, a switch, a test brush on said switch, means for moving said switch to cause said brush to traverse the test contacts of said circuits, a test magnet for said switch, a pair of windings on said magnet, means to provide a flow of current through one of said windings, a circuit for 100 said other winding including said test brush and said contacts successively, the flow of current through the second winding from the test contacts of busy circuits being in a direction to oppose the flow through the first mentioned winding, and the flow of current 105 through said second winding being in a direction to assist said first mentioned winding when the contact of an idle circuit is engaged.

8. In a telephone system, connecting circuits, multiple test contacts for said circuits respectively, means for supplying the test contacts of busy circuits with busy potential, a switch, a test brush on said switch, means for moving said switch to cause said brush to traverse test contacts of said circuits, a test magnet for said switch, a pair of windings on said magnet, means to provide a flow of current through one of said windings which is insufficient to operate said 115 magnet, a circuit for said other winding including said test brush and said contacts successively, the flow of current through the second winding from the test contacts of 120 busy circuits being in a direction to oppose 125

the flow through the first mentioned winding, and the flow of current through said second winding being in a direction to assist the first mentioned winding when the contact of an idle circuit is engaged.

9. In a telephone system, connecting circuits, multiple test contacts for said circuits respectively, means for supplying the test contacts of busy circuits with busy potential, a switch, a brush on said switch, a stepping magnet for moving said switch to cause said brush to traverse test contacts of said circuits, a side switch, a circuit for said stepping magnet including a wiper of said side switch, an operating magnet for said side switch, a pair of windings on said operating magnet, means to provide a flow of current through one of said windings which is insufficient to operate said magnet, and a circuit for said other winding including said test brush and said contacts successively, the flow of current through the second winding from the test contacts of busy circuits being in a direction to oppose the flow through the first mentioned winding.

10. In a telephone system, connecting circuits, multiple test contacts for said circuits respectively, means for supplying the test contacts of busy circuits with busy potential, a switch, a brush on said switch, a stepping magnet for moving said switch to cause said brush to traverse test contacts of said circuits, a side switch, a circuit for said stepping magnet including a wiper of said side switch, an operating magnet for said side switch, a pair of windings on said operating magnet, means to provide a flow of current through one of said windings which

is insufficient to operate said magnet, and a circuit for said other winding including said test brush and said contacts successively, the flow of current through the second winding from the test contacts of busy circuits being in a direction to oppose the flow from the first mentioned winding, and the flow of current through said second winding being in a direction to assist said first mentioned winding when the contact of an idle circuit is engaged.

11. In a telephone system, an electrically operated switch, a circuit extending to said switch, multiply connected guarding contacts for said connecting circuit, one of said contacts being in one of the conductors of said circuit, a source of current, an impulse relay for connecting said source to said conductor, a controlling magnet for said switch, means for joining said magnet to said conductor, a second source of current of different potential from said first mentioned source in series with said magnet, a second switch having a brush arranged to engage one of said multiple contacts, a test magnet for said second switch, a pair of windings on said magnet, means to provide a flow of current through one of said windings which is insufficient to operate said magnet, and a circuit for said other winding including said brush and said multiple guarding contact, the flow of current through said second winding being in a direction to oppose the flow through the first winding.

In witness whereof, I hereunto subscribe my name this 13th day of January, A. D. 1916.

ALBEN E. LUNDELL.
